UNITED STATES PATENT OFFICE.

THEODORE G. McGIRR, OF SPRINGFIELD, MASSACHUSETTS, ASSIGNEE, BY MESNE ASSIGNMENTS, TO PAVO MACHINE CO. INC., A CORPORATION OF NEW YORK.

CIGAR-BANDING MACHINE.

Application filed June 20, 1922. Serial No. 569,667.

To all whom it may concern:

Be it known that I, THEODORE G. McGIRR, a citizen of the United States, residing at Springfield, in the county of Hampden and 5 State of Massachusetts, have invented or discovered certain new and useful Improvements in Cigar-Banding Machines, of which the following is a specification, reference being had therein to the accompanying 10 drawings.

This invention relates to a machine for banding cigars, and more particularly for placing ornamental name bands on box cigars, although it may also be used for 15 banding bundle or loose cigars. A preferred embodiment of the invention is illustrated in the accompanying drawings and is hereinafter described, although it will be understood that the invention is not to be 20 considered as being limited to the particular constructions shown and described, and that the several features of the invention set forth in the claims forming part of this specification may be varied widely, within 25 the province of mechanical skill, without departing from the essence of the invention covered by said claims.

In the drawings Fig. 1 is an end view of a machine embodying the invention. Fig. 2 is a front side view of the same looking 30 from the right of Fig. 1. Fig. 3 is a section on line 3—3, and Fig. 4 a section on line 4—4, Fig. 1, looking in the direction denoted by the arrows adjacent said lines. Fig. 5 is a plan view of the improved machine. Fig. 6 is a detail plan view of the gearing shown in Figs. 1 and 5. Figs. 7, 8, 9 and 10 are fragmentary views of a cigar holder and band nipper and operating parts 35 for the same. Fig. 11 is a detail perspective view of a movable jaw of a cigar holder. Fig. 12 is a detail perspective view of a band nipper. Figs. 13 and 14 are detail views of the heated drier and co-operating parts. Figs. 15, 16 and 17 are detail views showing 40 the band feeding mechanism, Fig. 16 being a section on line 16—16. Fig. 15. Fig. 18 is a detail plan view of the cigar fingers and tilting carrying arms, together with some connected parts. Figs. 19 and 20 are detail 45 views of the cigar feeding mechanism, Fig. 19 being a side view and Fig. 20 a broken out plan view. Fig. 21 is a detail plan view of a fixed plate controlling the pawl from 50 which the intermittently travelling feeding

belts are operated. Figs. 22 and 23 are detail views of the moistening mechanism. Figs. 24, 25 and 26 are detail views of the ejecting or discharging mechanism. Figs. 27 and 28 are detail views illustrating the means by which the cigars are presented to 60 a cigar holder on the cigar carrier. Figs. 29 to 34, inclusive, are detail views illustrating the operation of wrapping a band around a cigar and finally sealing the same, the operations illustrated in these views following 65 the operations indicated in Figs. 27 and 28. Fig. 35 is a detail view showing the band folder and its operating mechanism.

Figs. 36 and 37 are detail views showing the operating mechanism of the heated drier 70 and the tucker plate.

Referring to the drawings, 12 denotes the frame of the machine at one side of which is mounted a power-driven shaft 13 carrying a worm 14 engaging a worm-wheel 15 having a clutch connection with a driving shaft 16 carrying a gear wheel 17 meshing with a similar gear wheel 18 on a shaft 19, said gear wheel 18 meshing with a similar gear wheel 20 on a shaft 21; all of the moving parts of the machine, being operated from the shafts 16, 19 and 21, as will hereinafter appear.

The shaft 21 is provided with an arm 22 carrying a pin 23 arranged to enter slots 24 of a wheel 25 mounted on a shaft 26 to impart an intermittent rotary movement to said shaft, this operating means for said shaft being the well-known "Geneva" mechanical movement. Fixed to the shaft 26, outside 85 of the frame of the machine, is a carrier wheel 27 having a circular series of holders which receive the cigars and maintain them in proper positions while the bands are being applied thereto. To this end each cigar holder comprises a fixed rectangular jaw 28 with which co-operates a movable jaw afforded by the outer end 29 of a bell-crank lever 29 fulcrumed on a pin 30 on the wheel 27, the inner end of the said bell-crank lever being connected by a coil spring 31 with a 90 pin 32, said spring serving to urge the outer end of the said bell-crank lever, affording the movable jaw, yieldingly towards the said fixed jaw 28 of the cigar holder. (See Fig. 27.) The bell-crank lever 29 is of double 95 form, as shown more clearly in the detail view Fig. 11, and the inner member of said lever carries a roller 33 resting against the

periphery of a cam disk 34 fixed to a hub 35 loosely mounted on the shaft 26. (See Fig. 7.)

Pivots mounted on the pin 30 is a lever 36 the outer end of which, in co-operation with the outer part 29^a of the bell-crank lever 29, affords a nipper for engaging and holding the ends of cigar bands, as will presently appear. The outer end of the nipper 36 is yieldingly pressed towards the outer end of said bell-crank lever by a coil spring 37 connecting the inner arm of said nipper lever with a pin 38 on the wheel 27, so as normally to press the outer end of said nipper lever towards the outer end of the bell-crank lever 29. The lever 36 is formed double, as shown more clearly in Fig. 12 and the inner member of said lever carries a roller 39 resting against the periphery of a cam disk 40 formed integral with or secured to the cam disk 34. (See Fig. 7.) The levers 29 and 36 are operated at proper times to open and close the cigar holder afforded by the fixed and movable jaws 28 and 29^a, as also to open and close the nipper afforded by the jaw 29^a and the outer end of the lever 36, by rocking movements imparted to the hub 35. To this end the hub 35 is provided with an arm 35^a to which is jointed a yoke 62 carrying a cam pin or roll 63 entering a cam groove 64 in a cam wheel 65 fixed to the driving shaft 16.

The bands to be applied to the cigars are held in a suitable magazine 41 having a partly open bottom, the bands being lightly supported at one end by a small projection or finger 42 at one end of the discharge opening in the bottom of the magazine. Mounted at the lower part of said magazine is a rock-shaft 43 carrying a recessed arm 44 which is provided with a perforated suction plate 45 overlying the recess or cavity in the said arm 44, the said recess or cavity opening into a suction duct 46 connected with a suction air pump 47 by a flexible pipe or hose 46^a. The piston rod 48 of the said suction pump is jointed to the lower end of a link 49 which is, in turn, jointed at its upper end to a lever 50 fulcrumed on the shaft 19 and carrying a pin or roller 51 engaging the periphery of a cam 52 fixed to the driving shaft 16. The rock-shaft 43 carries a gear 54 engaged by a rack 55 at the upper part of a bar 56 jointed at its lower end to a lever 57 fulcrumed on the shaft 16 and carrying a cam roll 58 entering a cam groove in a cam disk 59 on the shaft 19. The duct 46 communicates with a pipe 60 carried by the arm 44 on the rock-shaft 43 and to which pipe the hose or flexible pipe 46^a, running to the air pump 47, is attached.

The bands which are to be fed from the magazine 41 will, in practice, preferably be

gummed at one end and will be withdrawn from said magazine by the suction arm 44. To this end the shaft 21 is provided with a gear wheel 66 meshing with a pinion 67 fixed to a short shaft 68 carrying a disk 69 dipping into a water tank 70. Normally running in contact with the disk 69 is a moistening wheel 71 carried by an arm 72 mounted on a shaft 73 longitudinally slideable in bearings in the frame 12. The shaft 73 is provided with a fixed arm 74 connected by a link 75 with a lever 76 pivoted at its lower end to a bracket 77 and carrying a cam roll 78 entering a cam groove 79 in a cam cylinder 80 attached to the shaft 19. The arm 72 is held against endwise movement on the shaft 73 but is intended to have a slight rocking movement on said shaft by virtue of a torsional spring 81 co-operating with a stationary lug or cam 82 on the machine frame. Thus as the reciprocating moistening roll 71 is carried over the gummed end of a band it will be held out of contact with said band by said stationary cam until it arrives at a point over the middle of the band when it will be forced momentarily against the band under the influence of the spring 81, thus moistening the middle part of the gummed end thereof, the moisture spreading over the said gummed end of the band when the said gummed end is folded down by the means to be presently described. Thus by applying the moisture only to one limited spot, so as to moisten the gum only sufficient to ensure a proper adherence, the moistened part will dry quickly in sticking down the gummed end of the band. The gummed part of the band to be moistened lies over a jaw 29^a, and to prevent moisture which might pass through the bands from moistening the outer face of the jaw, and thus tend to cause adherence of the succeeding band thereto, the jaws 29^a are each preferably provided at their outer faces with a groove 29^b (Fig. 11) which will be beneath the parts of the bands touched by the moistening wheel.

It is obvious that the mechanism just described might be utilized for applying an adhesive to unguammed bands, if desired, by filling the tank 70 with liquid adhesive instead of water.

In the operation of the machine a band is withdrawn from the bottom of the magazine 41 by the suction arm 44, and the end of the band is inserted between the parts of the nipper afforded by the jaw 29^a of a bell-crank lever 29 and the jaw at the outer end of a lever 36, as hereinbefore mentioned, the nipper being then closed by the action of a spring 37 acting on said lever, thus laying the band across the top of a stationary cigar-holding jaw 28 and a movable jaw 29^a in readiness for the reception of a cigar to be inserted in a cigar holder.

The cigars to be banded are placed on a table α from which they may be manually pushed forward so as to come between two intermittently and coincidentally moving feeding belts 83 and 84. The mechanism for operating said belts comprises a sprocket-wheel 85 fixed to the shaft 19 and connected by a chain 86 with a sprocket-wheel 87 loosely mounted on a shaft 88. Rigid with the sprocket-wheel 87 is a disk 82 to which is pivoted a pawl 89 arranged to engage, at intervals, a ratchet wheel 90 fixed to said shaft 88, said pawl being held out of engagement with said ratchet wheel during the greater part of a revolution of the disk 82 by a fixed plate 91, but being permitted, by a flattened peripheral portion of said plate, to engage said ratchet-wheel only during a few degrees of revolution of said disk 91 and the sprocket-wheel 87 with which said disk is rigidly connected, thus imparting an intermittent rotary movement to said shaft 88.

Fixed to the shaft 88 is a gear wheel 92 meshing with a similar gear wheel 93 on a shaft 94. Mounted on the shafts 88 and 94 are pulleys 95 around which and suitably mounted idler pulleys 96 the intermittently moving feeding belts 83 and 84 run. The lower reach of the upper feeding belt 83 is pressed yieldingly downward by a weighted roller 97 carried by a pivoted arm 98. Proper tension is given to the lower feeding belt 84 by a belt tightening roller 99 carried by an arm 100 pivoted on the shaft 94, said roller being pressed yieldingly upward by a spring 101 connected with a pin 102 carried by the hub of the arm 100.

The cigars fed forward by the intermittently travelling belts 83 and 84 are moved beneath yielding plates 103 at the forward part of a frame 104 pivotally mounted at its rear end on the shaft 88, said frame carrying a bracket 105 from which a threaded pin 106 extends upward through a bracket 107 attached to a housing 108. On the threaded pin 106 is a thumb nut 109 which may be turned to vary the height of the frame 104 to accommodate cigars of different sizes. The cigars, when beneath the plates 103, rest on fingers 110, said fingers, which are spaced apart, being connected so as to move together and are rigid with arms 111 one of which carries a roll 112 against which a spring-held arm 113 rests. When the fingers are forced downward, as will presently be described, the arm 111 will be lifted and the arm 113 will move beneath the roll 112 which will now rest on the top of said arm 113 and against a stop 114, thus holding the fingers 110 in lowered position until the said fingers are again raised to their normal position, as will appear later.

When a cigar is resting on the fingers 110

and beneath the spring plates 103 it will be beneath a vertically reciprocating plunger 115 yieldingly mounted on a rod 116 carried by a block 117 connected with a rack 118 engaged by a sector gear 119 fixed to a rock-shaft 120 journalled in the machine frame. Fulerumed on the carrier shaft 26 is a lever 121 provided with a cam roll 122 entering a cam groove 122 in a cam-wheel 123 fixed to the shaft 21. The lever 121 is connected by a link 124 with an arm 125 secured to the shaft 120, and, by the operation of the parts just described, a rocking movement will be imparted to said shaft 120, as will be understood, to reciprocate the plunger 115 at proper intervals.

Box cigars to be banded are first tightly packed in the boxes while damp and assume an approximately square or four-sided shape when left in the boxes overnight or for a longer time. In thus packing the cigars in the boxes the top layer of each box is formed of selected cigars, and it is desirable that the top layer should constitute the top layer of the box after the cigars have been re-banded and repacked. To this end the contents of a box are lifted out of the box by a flexible strip or ribbon which is generally placed in the box beneath the cigars when the box is being packed, and in feeding the cigars to the present improved machine the contents of a box are placed in an open-bottomed receptacle on the table α and at one side of the feeding belts 83 and 84. By means of a flat pusher the bottom layer of cigars in the open-bottomed receptacle, (which loosely holds the contents of the box, with the cigars in the order in which they were packed) is shoved from the receptacle to a position in line with the said feeding belts, and then the entire layer is pushed forward manually between said belts which are of proper length to receive such layer. When a layer of cigars is thus pushed in manually between the feeding belts the layer fills the space between the stop 200 and the rear ends of the belts, and this entire layer will be automatically fed forward by the said belts, which travel in unison, without turning the cigars or rolling them over. When the cigars are banded they are to be repacked in a box, and as the lower layers are banded first the top layer of selected cigars will come last and will thus assume its original position in the top of the box, as is desirable.

The present machine is so constructed that the broader central or name portion of a band will come uppermost when the band is applied to a cigar placed in a holder, comprising fixed and movable jaws 28 and 29, and as each cigar will be given a quarter turn during a quarter turn, or of 90° of movement, of the carrier wheel 27, from the feeding-in to the discharging posi-

tion of said carrier wheel when the latter is intermittently rotated in the direction denoted by the arrow in Fig. 1, it is necessary, in order that the name portion of the 5 bands should be uppermost when the cigars are discharged from the rotating carrier onto the receiving table α that, before a cigar is placed in the carrier, it should be given a quarter turn in a direction opposite 10 the quarter turn it will get when in the carrier wheel.

To this end a tilting carrying device, having a reciprocating movement of 90° is provided. This tilting device, in the form 15 herein shown, comprises two notched arms 125 fixed to a rockshaft 126, the receiving notches in said arms being directly beneath the vertically reciprocating plunger 115 so that when said plunger descends a cigar 20 resting on the fingers 110 will be forced down with said fingers into the notched or receiving portions of the arms 125 and will be removably or frictionally held in said arms by the springs 127 mounted on said arms. 25 The shaft 126 is journalled in fixed bearings supported by the frame of the machine and is provided at its inner end with a mutilated sector-gear 128 meshing with a mutilated sector gear 129 loosely mounted 30 on the shaft 120, and operated as will presently be described, so that a quarter turn movement will be imparted to the tilter arms 125 at the proper intervals. (See Fig. 3.)

35 The tilter or tilting carrier arms 125, in their turning movements from the position shown by full lines to the position denoted by dotted lines in Fig. 19 will carry a cigar downward so as to locate it in register with 40 a holder comprising the jaws 28 and 29^a and across which jaws a band has been placed, as hereinbefore described, and the cigar will then be forced forward into said holder, pushing the band inward in the holder and 45 partly around the cigar, by a horizontally reciprocating feeder or pusher working beneath said tilting carrier and comprising spring arms 130 and 131 and a pushing member 132, these parts being all connected 50 with and operated by a rack-bar 133, the teeth of which mesh with a sector gear 134 mounted on a rock-shaft 135 and having a short arm 136 connected by a link 137 to the lower end of a lever 138 fulcrumed on 55 the shaft 21 and having a cam roll 139 entering a groove in a cam wheel 140 on the shaft 19. The rock-shaft 135 is also provided with an arm 141 connected by a link 142 with the sector gear 129 from which the 60 tilting carrier arms 125 are operated.

When a holder carried by the intermittently rotating carrier wheel 27 arrives at a station just previous to the station where the cigar is to be placed in a holder, as just 65 described, the moistening wheel 71 moves

outward and moistens the gummed portion of a band held by the nippers 29^a and 36, as hereinbefore described, returning thereafter to its inner position in engagement with the moistening disk 69. 70

When a cigar has been placed in a holder, as above described, with the band partly around it, and with the gummed portion of the band properly moistened, but with the ends of the band (meanwhile released from the nipper jaws 29^a and 36) extending outward from the holder, the upper end of the band will be pushed down by the descending and inwardly moving folder 143, and the same end 75 is then pushed inward beneath the cigar by the horizontally reciprocating tucker plate 144; and then, in the further rotation of the carrier wheel, the lower end of the band will be pressed inward over the tucked- 80 in moistened gummed portion thereof by the curved and yielding presser plate 145 along which the cigar is moved, with the band in contact therewith, thus fully closing the 85 band around the cigar. 90

The folder 143 is fixed to a holder 146 pivotally mounted on a pin 147 carried by a lever 148 fulcrumed on the shaft 26, said lever being jointed to the upper end of a yoke 149 carrying a cam pin or roll 150 engaging a cam groove in a cam wheel 151 on the second cam shaft 19. The holder 146 is provided with an arm 152 having an inclined end 152^a contacting with the upper 100 end of the yoke 149, said arm 152 being held upwardly in contact with an adjustable stop 153 by a coil spring 154, so that as the holder 146 moves downward with the lever 148 the said holder will be given a slight 105 turning movement, causing an inward movement to be imparted to the said folder 143 as it moves forward. See Fig. 35.

The tucker plate 144 is carried by an arm 155 fixed to a rock-shaft 155^a mounted on a suitable support 155^b, said rock-shaft having a second arm 155^c fixed thereto and carrying a roller 155^d yieldingly held, by a spring 155^e, in contact with the periphery of the cam wheel 151 carried by the second shaft 19 and having a peripheral cam 115 projection 151^f to engage said roller 155^d to operate said tucker plate at the proper intervals. (See Figs. 13 and 36.) The arm 155^c is provided with a pin 155^t to which said spring 155^e is attached, the other end 120 of said spring being connected to any suitable fixed part of the machine.

A band wrapped around a cigar as just described is, at the station of the carrier wheel next below that at which the cigar 125 was inserted in said wheel, subjected to the action of a preferably electrically heated drier which is yieldingly pressed against the band during a pause in the rotation of the carrier wheel 27. This drier will preferably 130

consist of a coil of resistance wire 159^a arranged to heat a plate 159 attached to a lever 160 pivoted on the rock-shaft 155^a and provided with a roller stud 161 held in yielding contact with a cam 162 on the second cam shaft 19, said cam being of proper form to move the drier outward away from the intermittently rotating carrier wheel when the latter is moving, but permitting said 10 drier to be drawn into contact with the bands during the intervals when the said carrier wheel is at rest by means of a spring 160^b one end of which is connected to a pin 160^a on a lever 160 and the other end of 15 which is secured to the frame. The inner portion of the cam 162 affords sufficient pauses or dwells to the heated drier, when the same is in contact with the bands, to enable said drier to properly seal the 20 gummed bands. (See Figs. 36, 13 and 14.)

When in the rotation of the carrier wheel 27 a banded cigar arrives at the station next beyond that at which the drier is located, the holder in which the cigar is held is 25 opened, to release the cigar, by the cam 34 acting on a bell-crank holding lever 29, and such released banded cigar will be moved out onto the table *z* by an ejector or discharging device comprising two parallel 30 arms 163 fixed to a shaft 163^a journalled in a reciprocating carriage 164 to which is jointed one end of a link 164^a connected at its other end to the upper end of an arm 165 on a rockshaft 166, said shaft having 35 a second arm 167 to which is jointed the lower end of a yoke 168 carrying a roller 169 engaging a cam 170 on the driving or first cam shaft 16. The arms 163 are provided with hooks 171 to engage the cigars 40 and carry them out beneath plate springs 172 pressing lightly thereon to keep them from turning, so that the name portions of the bands will remain uppermost, for convenient proper packing of the banded cigars 45 in the boxes. Co-operating with the springs 172, in holding the cigars from turning, are plate springs 173 on the hooked arms 163.

The hooked ejecting or discharging arms, as they reciprocate back and forth, are given 50 rising and falling movements by means of a yieldingly mounted lever 174 having an inclined portion 175 up which runs a roller 176 on the inner arm 163, said lever being normally held against stops 176^a by a spring 55 177 which will yield when the hooked arms are moving backward and when the incline 175 is engaged by the roller 176 and said roller is running up the incline 175 to lift the hooked arms 163. The lever 174 is pivoted at its lower end to a bracket 177^a integral with which are formed track members 178 and 179 the forward ends of said track members affording the stops 176^a. The top 60 portion of the lever 174, when said lever is 65 in contact with the stops afforded by the

track members 178 and 179, forms an extension of the upper track member 178 to hold the hooked arms 163 up when said arms are moving forward to discharge a cigar from the carrier wheel 27 onto the discharge 70 table *z*. When in the forward movement of the carriage 164 the roller 176 reaches the forward end of the upper track member 178 the said arms will fall by gravity so that the roller 176 will now rest on the lower track member 179 over which it will travel in its backward movement until it reaches the incline 175 when it will push the lever 174 backward against the stress of the spring 177 and will 75 ride up said incline and lift the hooked arms 163 for their next operation in discharging a cigar. When the carriage 164 next starts forward the lever 174 will also move forward, due to the stress of the spring 177, assisted slightly by the traction of the roller 176 on the upper track portion of the lever 174, thus again completing the upper track. From this it will be understood that 80 a properly timed four-motioned movement will be imparted to the hooked arms 163 in discharging the banded cigars from the carrier wheel 27 onto the receiving table *z*. 85

The operation of the machine, which will be generally understood from the foregoing, 90 is as follows: A box layer of cigars, placed on the table *z* in front of the feeding belts 83 and 84 will, while the machine is at rest, be manually shoved forward by the attendant between said belts with the foremost cigar against the stop 200. The machine being now started by throwing in the clutch on the driving shaft 16, to connect said shaft with the power shaft 13, the suction arm 44 withdraws a gummed band from the bottom 95 of the magazine 41 and presents it to the jaws 29^a and 34 of the band nipper on the intermittently rotating carrier wheel 27, and as the said wheel is moved forward in the direction denoted by the arrow in Fig. 1 the 100 nipper jaws, which have closed to nip the end of the band, will draw the said band from the bottom of the magazine and lay it over a cigar holder consisting of a movable jaw 29^a and a fixed jaw 28. At this forward movement of the carrier wheel the band thus laid over the holder arrives at 105 what may be termed the second station, and the moistener wheel then moves outward 110 over and applies water to the gummed end of the band still held by the band nipper; and the next forward movement of the carrier wheel brings the holder with the moistened band lying across the same to the 115 third station where a cigar is to be inserted in the holder. A cigar resting on the supporting fingers 110 at the forward ends of the feeding belts is, by the downward movement of the plunger 115, forced into the receiving recesses of the tilting carriers 125, 120 125 130

6 this downward movement of said plunger also forcing the yielding fingers 110 down; and the roller 112, carried by the arm 111 moving with said fingers, now rides up onto 5 the upper end of the spring-held arm 113 and against the stop 114 to hold the said fingers in its lowered position until the said arm 113 is released. The tilting carrier arms 125, now turn down to the position denoted by dotted lines in Fig. 19 carrying the 10 cigar down so that it will be in register with the holder across which the band lies. The pusher 132 next moves forward with the rack-bar 133 and moves the cigar, loosely 15 held by the tilting carrier arms 125 and the co-operating springs 127, into the holder, and the movable jaw 29^a of a bell-crank lever 29 is then closed against the cigar by the action of a spring 31, as permitted by 20 the cam 34. When the cigar is forced forward into the holder the band lying across the holder is pushed inward by the cigar so as to be partly around the cigar, but with the ends of the band extending outward. 25 The folder 143 now descends, moving inward as it does so, thus bending the upper end of the band inward towards the cigar, and the tucker plate 144 then moves inward and tucks said end under the cigar. The 30 next forward movement of the carrier wheel 27 carries the cigar downward along the yielding presser-plate 145 which presses the lower end of the band inward against the moistened gummed end of the band, as the 35 cigar is advanced, thus fully wrapping the band around the cigar. The cigar has now arrived at what may be termed the fourth station, where the heated drier 159 is located, and said drier is now momentarily 40 presesd against the band to dry the same and complete the sealing of the band around the cigar. The next forward movement of the carrier wheel 27 carries the cigar, with the band sealed around the same, to the fifth 45 or discharging station at the lower side of the said carrier wheel, and as the movable jaw of the holder will now have been opened by the action of the cam 34, the cigar will be released from the holder. The ejector or 50 discharging device, comprising the carriage 164 and the arms 163, now moves forward and the hooks 171 on said arms will engage the cigar on opposite sides of the wheel 27 and draw it forward onto the table α and beneath the spring plates 172 lightly pressing 55 on the cigar to keep it from rolling or turning over. As the cigars will each be given a quarter turn of 90° in one direction by the tilting carrier 125, and will be 60 given a quarter turn of 90° in the opposite direction, when moving from the third or feeding-in station, where said tilting carrier is located, to the fifth or discharging station, the cigars will be discharged onto the 65 table α , with their same sides uppermost as

were uppermost when the cigars were on the table α and between the feeding belts 83 and 84 which, as hereinbefore stated, move in unison so as to carry the cigars forward without turning them over or rolling them. 70

When the pushing member 132 moves forward to force a cigar from the down-turned tilting carrier arms 125 into a cigar holder on the carrier wheel 27 a laterally extending hook or projection 132^a on said pushing member engages the arm 113 forcing said arm forward and thus lifting the cigar supporting fingers 110 in readiness to receive the cigar next fed forward by the intermittently moving feeding belts 83 and 84, this movement of the arm 113 permitting the arm 111 and the roll 112 carried thereby to drop to their normal positions. 80

From the foregoing it will be understood that an entire box layer of cigars, manually placed between the feeding belts 83 and 84, will be automatically fed to the intermittently rotating carrier wheel 27 and will be automatically banded, and will then be discharged with their same sides uppermost 85 as were uppermost when the cigars were between said feeding belts. Thus the machine may be run more rapidly than banding machines now in use and to which the cigars have to be fed one at a time by the attendant, and the cigars will come from the banding machine with their proper sides up 90 in readiness to be quickly packed in the boxes. 95

Having thus described my invention, I 100 claim and desire to secure by Letters Patent:

1. In a cigar banding machine, a rotary carrier provided with a series of cigar holders each comprising a stationary jaw and a movable spring-pressed jaw, combined with a band nipper for each of said 105 holders, said band nipper comprising a spring-pressed lever co-operating with one of said jaws, and means for operating said spring-pressed jaw and lever in opposition to the stress of their closing springs. 110

2. In a cigar banding machine, a rotary carrier provided with a series of cigar holders each comprising a stationary jaw and a movable spring-pressed jaw, combined with a band nipper for each of said 115 holders, said band nipper comprising a spring-pressed lever co-operating with one of said jaws, and means for operating said spring-pressed jaw and lever in opposition to the stress of their closing springs, said means consisting of rocking cams, and members engaging said cams and acting on said movable spring-pressed jaw and lever. 120

3. In a cigar-banding machine, the combination with a rotary carrier and cigar holders and band nippers mounted on said carrier, of a band-holding magazine having a partly open bottom, a vibrating suction arm, and a rock-shaft by which said arm 125 130

is carried, said suction arm serving to remove the bands from said magazine, one by one, and present them to said nippers.

4. In a cigar-banding machine, the combination with a rotary carrier and cigar holders and band nippers mounted on said carrier, of a band-holding magazine having a partly open bottom, a vibrating suction arm located beneath said magazine and serving to remove the bands from said magazine, one by one, and present them to said nippers, and an exhaust air pump operatively connected with said suction arm.

5. In a cigar banding machine, the combination with a rotary cigar carrier and means for wrapping gummed bands about cigars, of a moistening device for the gummed bands, and a vibrating heated drier which is impressed against the bands when closed about the cigars, said drier being mounted outside of but closely adjacent to the periphery of said carrier.

6. In a cigar banding machine, the combination with a rotary cigar carrier and means for intermittently rotating the same, of means for wrapping gummed bands around the cigars, a heated drier for drying the bands before they are discharged from said carrier, said drier being mounted outside of but adjacent to the periphery of said carrier, and means for moving said drier from and towards said carrier.

7. In a cigar banding machine, the combination with means for wrapping gummed bands around the cigars and for holding the cigars while the bands are being wrapped around them, of a vibrating heated drier movable towards and from the banded cigars, and means for holding the heated drier against the bands on the cigars for periods of time sufficient to seal the gummed bands which encircle the cigars.

8. The combination with an intermittently rotating cigar carrier provided with a series of cigar holders and a series of band holding nippers, of means for presenting gummed bands to said nippers, means for wrapping the bands around the cigars, a heated drier for drying the bands, when wrapped around the cigars, before the cigars are discharged from said carrier, said drier being mounted outside of but adjacent to the periphery of said carrier, and means for moving said drier from and toward said carrier.

55. 9. In a cigar banding machine, a rotary cigar carrier provided with a series of cigar and band-holding devices each comprising a stationary cigar-holding jaw, a movable spring-closed cigar-holding jaw co-operating with said stationary jaw, and a movable spring-closed band-holding jaw co-operating with and pressing against said movable cigar-holding jaw.

60. 10. In a cigar banding machine, a rotary

cigar carrier provided with a series of cigar and band-holding devices each comprising a stationary cigar-holding jaw, a movable spring-closed cigar-holding jaw co-operating with said stationary jaw, and a movable spring-closed band holding jaw co-operating with and pressing against said movable cigar-holding jaw, combined with means for intermittently rotating said carrier, means for presenting previously gummed bands to said carrier, means for wrapping the bands, presented to said carrier, about the cigars, means for moistening the gummed bands, and heated pressure means for drying the bands when wrapped around the cigars, before the cigars are discharged from said carrier.

11. In a cigar banding machine, the combination with an intermittently rotating cigar carrier having a series of cigar holders, of means for feeding bands and wrapping them around the cigars, two intermittently travelling feeding belts for advancing the cigars towards said carrier and between which belts the cigars are placed, means, beyond said belts, for temporarily supporting each cigar when advanced beyond the forward ends of said belts, a reciprocating plunger arranged to act on the cigars thus temporarily supported, and a tilting carrier adapted to receive the cigars and into which carrier the cigars are forced by said plunger.

12. In a cigar banding machine, the combination with an intermittently rotating cigar carrier having a series of cigar holders, of means for feeding bands and wrapping them around the cigars, two intermittently travelling feeding belts for advancing the cigars towards said carrier and between which belts the cigars are placed, means, beyond said belts, for temporarily supporting each cigar when advanced beyond the forward ends of said belts, a reciprocating plunger arranged to act on the cigars thus temporarily supported, a tilting carrier adapted to receive the cigars and into which carrier the cigars are forced by said plunger, and means for imparting a quarter turning movement to said tilting carrier.

13. In a cigar banding machine, the combination with an intermittently rotating cigar carrier having a series of cigar holders, of means for feeding bands and wrapping them around the cigars, two intermittently travelling feeding belts for advancing the cigars towards said carrier and between which belts the cigars are placed, means, beyond said belts, for temporarily supporting each cigar when advanced beyond the forward ends of said belts, a reciprocating plunger arranged to act on the cigars thus temporarily supported, a tilting carrier adapted to receive the cigars and into which carrier the cigars are forced by said plunger,

and a reciprocating pusher for removing the cigars from said tilting carrier and placing them in the holders of said rotating carrier.

14. In a cigar banding machine, the combination with an intermittently rotating cigar carrier having a series of cigar holders, of means for feeding bands and wrapping them around the cigars, two intermittently travelling feeding belts for advancing the cigars towards said carrier and between which belts the cigars are placed, means, beyond said belts, for temporarily supporting each cigar when advanced beyond the forward ends of said belts, a reciprocating plunger arranged to act on the cigars thus temporarily supported, a tilting carrier adapted to receive the cigars and into which carrier the cigars are forced by said plunger, means for imparting a quarter turning movement to said tilting carrier, and a reciprocating pusher for removing the cigars from said tilting carrier and placing them in the holders of said rotating carrier.

25 15. In a cigar banding machine, the combination with an intermittently rotating cigar carrier having a series of cigar holders, of means for feeding bands and wrapping them around the cigars, two intermittently travelling feeding belts for advancing the cigars towards said carrier and between which belts the cigars are placed, means, beyond said belts, for temporarily supporting each cigar when advanced beyond the forward ends of said belts, a reciprocating plunger arranged to act on the cigars thus temporarily supported, a tilting carrier adapted to receive the cigars and into which carrier the cigars are forced 30 by said plunger, a reciprocating pusher for removing the cigars from said tilting carrier and placing them in the holders of said rotating carrier, and a discharging device for removing the cigars from said carrier 35 without turning the cigars.

45

16. In a cigar banding machine, the combination with an intermittently rotating cigar carrier having a series of cigar holders, of means for feeding bands and wrapping them around the cigars, two intermittently travelling feeding belts for advancing the cigars towards said carrier and between which belts the cigars are placed, means, beyond said belts, for temporarily supporting each cigar when advanced beyond the forward ends of said belts, a reciprocating plunger arranged to act on the cigars thus temporarily supported, a tilting carrier adapted to receive the cigars and into which carrier the cigars are forced by said plunger, means for imparting a quarter turning movement to said tilting carrier, a reciprocating pusher for removing the cigars from said tilting carrier and placing them in the holders of said rotating carrier.

ing carrier, and a discharging device for removing the cigars from said carrier without turning the cigars.

17. In a cigar banding machine, the combination with an intermittently rotating cigar carrier having a series of cigar holders, of means for feeding bands and wrapping them around the cigars, two intermittently travelling feeding belts for advancing the cigars towards said carrier and between which belts the cigars are placed, means, beyond said belts, for temporarily supporting each cigar when advanced beyond the forward ends of said belts, a reciprocating plunger arranged to act on the cigars thus temporarily supported, a tilting carrier adapted to receive the cigars and into which carrier the cigars are forced by said plunger, a reciprocating pusher for removing the cigars from said tilting carrier and placing them in the holders of said rotating carrier, a discharging device for removing the cigars from said carrier without turning the cigars, and means for holding the cigars from turning after they are discharged from said carrier. 70 75 80 85 90 95

18. In a cigar banding machine, the combination with an intermittently rotating cigar carrier having a series of cigar holders, of means for feeding bands and wrapping them around the cigars, two intermittently travelling feeding belts for advancing the cigars towards said carrier and between which belts the cigars are placed, means, beyond said belts, for temporarily supporting each cigar when advanced beyond the forward ends of said belts, a reciprocating plunger arranged to act on the cigars thus temporarily supported, a tilting carrier adapted to receive the cigars and into which carrier the cigars are forced by said plunger, means for imparting a quarter turning movement to said tilting carrier, a reciprocating pusher for removing the cigars from said tilting carrier and placing them in the holders of said rotating carrier, a discharging device for removing the cigars from said carrier without turning the cigars, and means for holding the cigars from turning after they are discharged from said carrier.

19. In a cigar banding machine, the combination with an intermittently rotating cigar carrier having a series of cigar holders, of means for feeding bands and wrapping them around the cigars, two intermittently travelling feeding belts for advancing the cigars towards said carrier and between which belts the cigars are placed, means, beyond said belts, for temporarily supporting each cigar when advanced beyond the forward ends of said belts, a reciprocating plunger arranged to act on the cigars thus temporarily supported, a tilting carrier adapted to receive the cigars 120 125 130

- and into which carrier the cigars are forced by said plunger, a reciprocating pusher for removing the cigars from said tilting carrier and placing them in the holders of said rotating carrier, and heated means for drying and thus finally sealing the bands while the cigars are still retained in said holders.
20. In a cigar banding machine, the combination with an intermittently rotating cigar carrier having a series of cigar holders, of means for feeding bands and wrapping them around the cigars, two intermittently travelling feeding belts for advancing the cigars towards said carrier and between which belts the cigars are placed, means, beyond said belts, for temporarily supporting each cigar when advanced beyond the forward ends of said belts, a reciprocating plunger arranged to act on the cigars thus temporarily supported, a tilting carrier adapted to receive the cigars and into which carrier the cigars are forced by said plunger, means for imparting a quarter turning movement to said tilting carrier, a reciprocating pusher for removing the cigars from said tilting carrier and placing them in the holders of said rotating carrier, and heated means for drying and thus finally sealing the bands while the cigars are still retained in said holders.
21. In a cigar banding machine, the combination with an intermittently rotating cigar carrier having a series of cigar holders, of means for feeding bands and wrapping them around the cigars, two intermittently travelling feeding belts for advancing the cigars towards said carrier and between which belts the cigars are placed, means, beyond said belts, for temporarily supporting each cigar when advanced beyond the forward ends of said belts, a reciprocating plunger arranged to act on the cigars thus temporarily supported, a tilting carrier adapted to receive the cigars and into which carrier the cigars are forced by said plunger, a reciprocating pusher for removing the cigars from said tilting carrier and placing them in the holders of said rotating carrier, heated means for drying and thus finally sealing the bands while the cigars are still retained in said holders, and means for holding the cigars from turning after they are discharged from said carrier.
22. In a cigar banding machine, the combination with an intermittently rotating cigar carrier having a series of cigar holders, of means for feeding bands and wrapping them around the cigars, two intermittently travelling feeding belts for advancing the cigars towards said carrier and between which belts the cigars are placed, means, beyond said belts, for temporarily supporting each cigar when advanced beyond the forward ends of said belts, a reciprocating plunger arranged to act on the cigars thus temporarily supported, a tilting carrier adapted to receive the cigars and into which carrier the cigars are forced by said plunger, means for imparting a quarter turning movement to said tilting carrier, a reciprocating pusher for removing the cigars from said tilting carrier and placing them in the holders of said rotating carrier, heated means for drying and thus finally sealing the bands while the cigars are still retained in said holders, a discharging device for removing the cigars from said carrier without turning the cigars, and means for holding the cigars from turning after they are discharged from said carrier.
23. In a cigar banding machine, the combination with an intermittently rotating cigar carrier having a series of cigar holders, of means for feeding bands and wrapping them around the cigars, two intermittently travelling feeding belts for advancing the cigars towards said carrier and between which belts the cigars are placed, means, beyond said belts, for temporarily supporting each cigar when advanced beyond the forward ends of said belts, a reciprocating plunger arranged to act on the cigars thus temporarily supported, a tilting carrier adapted to receive the cigars and into which carrier the cigars are forced by said plunger, a reciprocating pusher for removing the cigars from said carrier without turning the cigars, heated means for drying and thus finally sealing the bands while the cigars are still retained in said holders, and means for holding the cigars from turning after they are discharged from said carrier.
24. In a cigar banding machine, the combination with an intermittently rotating cigar carrier having a series of cigar holders, of means for feeding bands and wrapping them around the cigars, two intermittently travelling feeding belts for advancing the cigars towards said carrier and between which belts the cigars are placed, means, beyond said belts, for temporarily supporting each cigar when advanced beyond the forward ends of said belts, a reciprocating plunger arranged to act on the cigars thus temporarily supported, a tilting carrier adapted to receive the cigars and into which carrier the cigars are forced by said plunger, means for imparting a quarter turning movement to said tilting carrier, a reciprocating pusher for removing the cigars from said tilting carrier and placing them in the holders of said rotating carrier, heated means for drying and thus finally sealing the bands while the cigars are still retained in said holders, a discharging device for removing the cigars from said carrier without turning the cigars, and means for holding the cigars from turning after they are discharged from said carrier.

In testimony whereof I affix my signature.
THEODORE G. McGIRR.
